UNITED STATES PATENT OFFICE.

EGBERT C. HOPKINS, OF ROCKFORD, ILLINOIS.

VAPOR-STOVE.

SPECIFICATION forming part of Letters Patent No. 292,315, dated January 22, 1884.

Application filed August 25, 1883. (No model.)

To all whom it may concern:

Be it known that I, EGBERT C. HOPKINS, a citizen of the United States, residing in the city of Rockford, in the county of Winnebago 5 and State of Illinois, have invented new and useful Improvements in Stoves, of which the following is a specification.

This invention relates to that class of stoves known as "vapor-stoves," in which the fluids employed as fuel are first transformed into a vapor and then burned.

The object of this invention is to utilize the heat produced from the burning vapors, and to provide an escape for the smoke or unburned particles of the vapors and other offensive gases arising from this class of stoves.

To this end I have designed and constructed the stove represented in the accompanying drawings, in which—

20 Figure 1 is an isometrical representation of a stove embodying my invention, in which a portion of the gas or smoke escape pipe is broken away to more clearly show the construction. Fig. 2 is also an isometrical representation of my improved stove, in which the upper plate or top of the stove is omitted. Fig. 3 is an elevation of one of the vapor-burners, showing its position relatively with the stove; and Fig. 4 is an isometrical representation 25 of a grated cover capable of use instead of the griddle-plates.

In the figures, A represents end standards, of open frame-work, connected toward their lower ends by means of horizontal rods *a*, on 35 which is supported a drip-shelf, B. These end standards and their connections constitute the supporting-frame of the stove.

The bottom plate of my improved stove consists of the plate portion C, provided with 40 openings *b*, of a proper size to receive the burners. These openings are provided with a depending ring portion, *c*, which serves to protect the flame of the burner supported therein from disturbing side air-currents, and 45 cause the heat generated by the burners to ascend into the stove. The outer edge portion of this bottom plate is provided with an up-rising rim, D, of suitable height. This vertical rim, on its front side, is provided with windows *d*, placed opposite the burners, through 50 which the burners can be seen without removing the articles placed over the burners.

At *e* is represented a center, rectangular in plan, rising from the center of the bottom plate to the same height of the uprising rim 55 on the outer edge of the plate.

At *h* is represented a vertical wall, radiating from the front side of the rectangular center, rising from the bottom plate to the height of the rectangular center and outer rim, with 60 which it connects, dividing the front half of the stove centrally between the burners into equal sections, E and F. The remaining three sides of the rectangular center *e* are each provided with a radial slot, *i*, to receive the journal end of a check-valve or damper, to oscillate therein freely. In the same radial line with the radial slots *i* the outer rim, D, is provided with vertical slots *h*, or otherwise fitted to receive the journal-bearing of a check-valve or 65 damper, to oscillate therein.

At *H* are represented check-valves or dampers of blade form, having their ends produced in journal form, fitted to enter and oscillate in the bearings in the rectangular center and 75 in the outer uprising rim, and serve as division-walls to the four equal divisions, E, F, I, and K.

At *L* is represented a stove-pipe support, projecting from the rear center of the bottom 80 plate. This support is divided into two sections, *l* and *n*, by a vertical wall, *m*, on the same radial line with the check-valve or damper, with the outer end of which it connects, and is employed to separate the rear chambers, I and K.

At *M* is represented the top or upper plate of the stove, provided in the usual manner with openings *N*, fitted in the usual manner with removable griddle-plates *P*, and is fixed 90 in place on the stove by means of suitable screw-bolts in its several corners. This upper plate is fitted with a collar, *o*, to receive a stove-pipe. This collar is of proper dimensions to engage the stove-pipe support, on 95 which it rests. This collar is provided with a central division-wall, *o'*, which connects with the vertical division-wall *m* of the support, and separates the collar into two equal sections, each of which is fitted with a check-valve or 100 damper, *o''* and *o'''*.

At *P'* is represented a section of a stove-pipe, a portion of which is broken away to show the valves in the stove-pipe collar and

its connection with the collar. This pipe is designed to connect with a suitable flue, or extend to communicate with the external air.

At P" is represented a supply-pipe having its lower end portion placed under the front portion of the stove, slightly rearward of a vertical plane passing through the centers of the openings b in the bottom plate. This portion of the supply-pipe is supported in an adjustable manner by means of slotted bearings p, having an adjustable connection with the slotted bars P" of the supporting-frame, on which the slotted bearings are made laterally and vertically adjustable, and held in their adjusted position by means of clamping-screws passing through the slotted parts. From this connection of the supply-pipe with the frame it extends rearward on one end of the stove, and rises through a loop-support, p', and having its upper end provided with a fluid-reservoir, R. From the horizontal portion of the supply-pipe, at proper intervals, rise branch pipes p", which connect with other branch pipes, p'", on which the burners are supported in the vertical center of the openings b in the bottom plate. The burners employed in this instance are of one of the known forms, consisting of a perforated dome, s, having a depending tube, t. A vertical valve-tube, s', provided with a cup, s", to contain fluid to heat the burner, is centrally connected with the branch pipe p'", which is provided with a needle-valve, s''', having a screw-thread connection with the axial center of the valve-tube, to engage the valve-seat in the upper end of the tube centrally under the depending tube t of the dome.

At T is represented an open grate, designed to be employed instead of the removable grid-plate when required.

In the use of my improved stove the fluid is admitted to the cup and to the burner in the usual way, and, when ignited, the valve or damper in rear of the burner and in the stove-pipe in the same chamber are opened, which will carry off all the smoke. When the burner has become sufficiently heated to generate gas properly, the dampers may be closed, and the heat produced utilized in heating the contents of the vessels placed in or over the opening over the burner. When such vessel is sufficiently heated, it may be placed on the opening in rear of the burner, and another vessel put in its place over the burner. The valve in rear of the burner is then opened, and the heat will extend to the rear chamber, to keep the contents of the vessel in the rear chamber hot. After the contents of the second vessel over the burner is sufficiently heated, it may be placed on the other rear opening and another vessel placed over the burner. The

valve between the two rear openings is then opened, which will permit the heat from the burner to keep the contents of the second vessel hot while the third vessel is heating.

In the use of my improved stove in the manner described, it will be necessary to properly adjust the valves in the stove-pipe collar to insure sufficient draft to properly support combustion and conduct the heated current to the chamber required, all of which will be readily suggested. It will also be seen that when the two burners are ignited, and the several dampers separating the chambers of the stove are opened, that vessels placed upon all the openings will be exposed to the heat generated by the burners.

From the foregoing it will be seen that in the use of my improved stove I am enabled to produce greater results from the consumption of a given amount of liquid fuel than can be produced in an open single-plate stove as ordinarily constructed. In the foregoing I have represented my improved stove with but two burners and four openings; but, evidently, this system may be reduced to a single burner, or it may be increased to any required extent by which its capacity may be increased to meet the requirements of large establishments.

I claim as my invention—

1. In a two-plate vapor-stove, the combination, with the plates, of a division-wall for separating the burners, and movable dampers arranged substantially as set forth, whereby each half of the stove may be heated by a separate burner, and the heat conveyed from said burner to the rear compartment of the other half of the stove.

2. The combination, in a two-plate vapor-stove, of a center fitted with journal-bearings, and a radial vertical division connecting the center with the outer rim separating the burners, substantially as and for the purpose set forth.

3. The combination, in a vapor-stove fitted with dampers or valves capable of use to separate the openings into separate and independent chambers, of a top plate provided with a pipe-collar fitted with valves or dampers communicating with the independent burner-chambers, substantially as set forth.

4. The combination, with the supply-pipe and with the supporting-frame, of adjustable bearings supporting said supply-pipe on the supporting-frame, and made adjustable thereon, substantially as and for the purpose set forth.

EGBERT C. HOPKINS.
